PHONOGRAPH RECORD HOLDER OR THE LIKE

Peter Ackeret, Kusnacht, Switzerland, assignor to IISI
Products AG, Chur, Switzerland

Filed Aug. 1, 1974, Ser. No. 493,542

Term of patent 14 years

Int. Cl. D6—04

U.S. Cl. D6—185

FIG. 1

FIG. 2

FIG. 3

FIG. 1

FIG. 2

FIG. 3

FIG. 1 is a perspective view of a phonograph record holder or the like showing my design;

FIG. 2 is a front view of the record holder of FIG. 1;

FIG. 3 is a rear view of the record holder of FIG. 1;

FIG. 4 is a top view of the record holder of FIG. 1;

FIG. 5 is a bottom view of the record holder of FIG. 1; and

FIG. 6 is a side view of the record holder of FIGS. 1-5, the other side being an identical mirror image of FIG. 6.

The ornamental design for a phonograph record holder or the like, as shown and described.
